UNITED STATES PATENT OFFICE.

REUBEN B. BENJAMIN, OF CHICAGO, ILLINOIS, ASSIGNEE TO BENJAMIN ELECTRIC MANUFACTURING COMPANY, OF CHICAGO, ILLINOIS, A CORPORATION OF ILLINOIS.

LAMP-SOCKET.

1,271,835.

Specification of Letters Patent. Patented July 9, 1918.

Application filed July 6, 1915. Serial No. 38,822.

To all whom it may concern:

Be it known that I, REUBEN B. BENJAMIN, a citizen of the United States, residing at Chicago, in the county of Cook and State 5 of Illinois, have invented new and useful Improvements in Lamp-Sockets, of which the following is a full, clear, concise, and exact description, reference being had to the accompanying drawing, forming a part of 10 this specification.

My invention relates to lamp sockets.

One of the objects of my invention is to provide an improved socket in which the insulating base carrying the contacts may 15 be secured within the casing in various positions of adjustment, and to provide an improved construction which is particularly advantageous in pull switch sockets, which will enable the pull member to be located in 20 the desired position.

In the drawings in which I have shown one embodiment of my invention

Figure 1 is a side elevation of a socket embodying my invention showing the openings in the casing into which the retaining fingers on the insulating base fit;

Fig. 2 is an axial section showing the manner in which the retaining fingers are secured on the insulating base and engage 30 the socket casing;

Fig. 3 is a side elevation of the insulating base and parts carried thereby removed from the casing, and showing a lamp in position;

Fig. 4 is a section on the line 4—4 of Fig. 2 showing the arrangement of the openings in the casing; and

Fig. 5 is a perspective view of one of the retaining fingers.

Referring now to the drawings in detail, the socket shown comprises a casing 10, an insulating base 11 for supporting the lamp contacts, and an insulating cup 12. The casing 10 may be formed from a single piece 45 of sheet material shaped to provide a threaded portion 13 for engagement with a lamp shade or holder, and is provided with the usual screw threaded bushing 14 for connection with a conduit for the feed wires.

The usual insulating lining 15 is provided at the upper end of the casing and has an opening 16 therein for the passage of the leading in wires. The casing 10 is also provided with a number of equally spaced 55 openings 17 to receive the rounded stamped

up ends 18 of the spring clips or retaining fingers 19 which are secured to the insulating base 11 by means of screws 20 extending through openings in the base and screw threaded into the base portions 22 of the 60 spring clips 19. The insulating cup 12 has an inwardly extending flange portion 23 to provide insulation between the spring clip 19 and the shell contact 28.

A pull switch of any suitable construction 65 may be mounted on the base 11 within the casing 10 and provided with an operating chain 24 which extends downwardly through a passage 25 in the base 11, between the cup 12 and casing 10 along the side of 70 the lamp bulb, as shown in Figs. 1 and 3.

The use of my improved socket is as follows: The bushing 14 is screwed tightly on a conduit after which the base 11 carrying the contacts and pull chains is inserted 75 within the socket so as to bring the pull chain 24 in the desired position, the base being adjusted until the stamped up ends 18 of the spring clips snap into a pair of the openings 17 in the casing 10 to hold the 80 base 11 within the casing. The openings 17 not only afford a means for securing the base 11 in the desired position, but also afford ventilation for the lamp. The base 11 fits snugly within the casing 10 and prevents any undesirable movement of the base 85 within the casing after the spring clips 19 have snapped into place. The base 11 may be removed from the casing 10 by pressing inwardly on the spring clips 19 with the 90 fingers or with any suitable tool. It is obvious that no matter in which position the casing 10 may be when the bushing 14 has 95 been screwed onto the conduit as far as it will go it will be possible to secure the base 11 in such a position that the pull chain 24 will be in the desired location.

Certain claims containing no reference to switch mechanism, but claiming features shown in this application, will be presented 100 in applicant's copending application Serial No. 69,890, filed January 3, 1916, or in applicant's co-pending application Serial No. 233,462, filed May 9, 1918.

Having thus described my invention what 105 I claim as new and desire to secure by Letters Patent is:—

1. A switch receptacle comprising an internally-threaded bushing, a cup-shaped housing non-rotatably secured with respect 110

- to said bushing, an insulating base in said housing, a contact and a switch-operating member supported by said base, said housing extending down over said contact, said 5 switch-operating member being offset with respect to the axis of said receptacle, and means for securing said base in said casing in different positions of rotatable adjustment.
- 10 2. A switch receptacle comprising an internally-threaded bushing, a cup-shaped housing non-rotatably secured with respect to said bushing, an insulating base in said housing, a contact and a switch-operating 15 member supported by said base, said housing extending down over said contact, said switch-operating member being offset with respect to the axis of said receptacle, and means for securing said base in said casing 20 in different positions of rotatable adjustment, said operating member comprising a pull member extending out through the open end of the cup-shaped housing.
3. A switch receptacle comprising an internally-threaded bushing, a cup-shaped 25 housing non-rotatably secured with respect to said bushing, an insulating base in said housing, a contact and a switch-operating member supported by said base, said housing extending down over said contact, said switch-operating member being offset with respect to the axis of said receptacle, and means for securing said base in said casing 30 in different positions of rotatable adjustment, said securing means comprising a spring tongue secured to said insulating base, said casing having a plurality of recesses in any one of which said tongue may enter.
4. A switch receptacle comprising an internally-threaded bushing, a cup-shaped 40 housing non-rotatably secured with respect to said bushing, an insulating base in said housing, a contact and a switch-operating member supported by said base, said housing
- extending down over said contact, said 45 switch-operating member being offset with respect to the axis of said receptacle, and means for securing said base in said casing in different positions of rotatable adjustment, said securing means comprising a 50 spring tongue secured to said insulating base, said casing having a plurality of recesses in any one of which said tongue may enter, said tongue extending outwardly from said insulating base. 55
5. A switch receptacle comprising an internally-threaded bushing, a cup-shaped housing non-rotatably secured with respect to said bushing, an insulating base in said housing, a shell contact and a switch-operating member supported by said base, said housing extending down over said contact, said switch-operating member being offset with respect to the axis of said receptacle, and means for securing said base in said 60 casing in different positions of rotatable adjustment, said operating member comprising a pull member extending between said shell contact and said housing, out through the open end of the housing. 65
- 70 6. A switch receptacle comprising an internally-threaded bushing, a cup-shaped housing non-rotatably secured with respect to said bushing, an insulating base in said housing, a shell contact and a switch-operating member supported by said base, said housing extending down over said shell contact, an insulating cup between said shell contact and the housing, and means for securing said base in said casing in different 75 positions of rotatable adjustment, said operating member comprising a pull member extending between said insulating cup and said housing and out through the open end of said housing. 80
- 85 In witness whereof I have hereunto subscribed my name.

REUBEN B. BENJAMIN.
